DESIGN FOR A COMBINED COAT HANGER AND JEWEL CONTAINER

Winnifred Melford, Los Angeles, Calif.

Application July 13, 1945, Serial No. 120,687

Term of patent 7 years

(Cl. D80—8)

To all whom it may concern:

Be it known that I, Winnifred Melford, a citizen of the United States and resident of the city of Los Angeles, county of Los Angeles, State of California, have invented a new, original, and ornamental Design for a Combined Coat Hanger and Jewel Container, of which the following is a specification, reference being had to the accompanying drawing, forming a part thereof, in which:

Fig. 1 is a top plan view of a combined coat hanger and jewel container showing my new design, the container being shown open on one side of the hook and closed on the opposite side.

Fig. 2 is a side view thereof.

I claim:

The ornamental design for a combined coat hanger and jewel container, substantially as shown.

Winnifred Melford.
